UNITED STATES PATENT OFFICE.

JOHN W. DOWDLE, OF MINERAL SPRINGS, ARKANSAS.

TYING DEVICE.

1,349,503.

Specification of Letters Patent. Patented Aug. 10, 1920.

Application filed December 10, 1918. Serial No. 266,075.

To all whom it may concern:

Be it known that I, JOHN W. DOWDLE, a citizen of the United States, residing at Mineral Springs, in the county of Howard 5 and State of Arkansas, have invented new and useful Improvements in Tying Devices, of which the following is a specification.

This invention has reference to a means whereby a package or bundle may be quickly 10 and securely tied.

The object of the invention is to provide a tying device so constructed that the arrangement thereof on a bundle will not inflict injury to the bundle, the said device 15 having means whereby one end of a tying cord is secured thereto and having clamping means for the end of the cord.

Other objects and advantages will appear as the nature of the invention is better understood, reference being had to the accompanying drawings, in which:

Figure 1 is a perspective view illustrating a package tied in accordance with this invention.

Fig. 2 is a similar view showing another manner in which the package may be tied.

Fig. 3 is a perspective view of the improvement.

In the drawings a bundle or package is 30 indicated by the numeral 5. This bundle or package is designed to be secured in accordance with the present invention.

The improvement is preferably constructed from a single strand of wire but may be 35 constructed of other resilient material.

As disclosed by the drawings, the ends of the wire body are bent upon themselves to provide outstanding angularly arranged eyes 6, and the eye portions are designed 40 to lap each other when a tying cord 7 is passed therethrough and the knotted end thereof contacts with one of the eyes. The legs 8—8 extending from the eyes 6 are approximately centrally of their length bent 45 upon themselves as at 9 and continued at a downward angle with respect to the legs, as indicated by the numerals 10, and from thence rounded and extending rearwardly as at 11, the ends of the said portions 11 being rounded downwardly as at 12, extended inwardly and upwardly as at 13, rounded as at 14 and continued in the same 50 direction, preferably in parallelism as indicated by the numeral 15. The portions 55 15 form the inner leg members, and the bent portions at the center of the legs pro-

vide reversely extending jaws which are broadly indicated by the characters A and B. The jaws A and B, thus formed on account of their location, direction of extension and resiliency, are adapted to receive with yielding and tying pressure, the free end of the tying cord to securely hold the same. When both jaws, A and B, are utilized for tying the cord said means admits 60 of employing said cord in a short turn that is held securely by the pressure of each jaw acting thereon. The ends of the legs 15 are extended laterally as at 16, having their outer ends rounded preferably downwardly 65 as at 17 and from thence continued inwardly 70 in the same plane as the portions 16. The outer wire members 17 are bent upwardly and thence downwardly, thence upwardly and again downwardly forming the center 75 of the said bent portion with what I will term a guide 18 for the tying cord. The lateral end of the body is preferably arched and forms a bridge which may be broadly indicated by the character C.

As disclosed in Fig. 1 of the drawings, the tying cord may be brought around the bundle 5, passed over the bridge C being received in the guide 18 and have the end thereof passed first through the jaw A and 80 then through the jaw B. It is here to be stated that the spring jaws, engage the cord with sufficient friction to firmly hold the same upon the device, so that it is not absolutely necessary to pass the cord through 85 both of the jaws. When the bundle is to be tied, as illustrated in Fig. 2 of the drawings, the cord is arranged around the bundle as above described, but is passed only through the jaw A. The cord is then passed 90 transversely over and into engagement with the jaw B. If desired, the cord may be also passed through the jaw A. The body portion, that is, the portion of the construction provided between the eyes and the bridge 95 100 of the device is preferably arched so that the same does not contact with the bundle, and it is believed, from the foregoing description, when taken in connection with the drawings, the simplicity and advantages 105 of the construction will be readily apparent without further detailed description.

It should be stated, however, that the cord is free from knots and that the fastening is made by a simple manipulation of 110 the hand, the cord being at all times of a sufficient length to permit of being applied

to any size package. As the cord is continuously used, the saving in this respect will, it is thought, be appreciated.

Having thus described the invention, what is claimed as new, is:—

1. A device for the purpose set forth, including a spring member having an arched body provided at one of its ends with an offset eye designed to receive therein one end of a tying cord, said body adapted to be centrally bent upon itself to form reversely extending spring jaws to provide a short turn frictional engagement for the free end of said cord, the second end of the body being extended laterally to provide a bridge, the said bridge being arched and being centrally formed with an upstanding cord guide, as and for the purpose set forth.

2. A package tying device constructed from a single strand of spring wire bent upon itself to provide a body comprising arched parallel strands of the said wire, said strands, at one of their ends being provided with angle eyes which lap and the said eyes designed to receive therethrough one end of a tying cord, the body adapted to be centrally bent upon itself to form reversely extending spring jaws, the strand of the body at the second end thereof being extended laterally and from thence rounded inwardly, the said rounded portion being bent to form a central cord guide, all as and for the purpose set forth.

In testimony whereof I affix my signature.

JOHN W. DOWDLE.
